UNITED STATES PATENT OFFICE

PETER MADSEN, OF BERLIN, GERMANY.

CAR-COUPING.

SPECIFICATION forming part of Letters Patent No. 291,753, dated January 8, 1884.

Application filed November 30, 1883. (No model.)

To all whom it may concern:

Be it known that I, PETER MADSEN, a subject of the Kingdom of Prussia, German Empire, residing at the city of Berlin, in the Kingdom of Prussia, German Empire, have invented certain new and useful Improvements in Railway-Car Couplings, of which the following is a specification.

This invention has reference to an improved coupling for passenger and freight cars, which can be operated from either side of the cars without requiring the brakeman to enter between the cars for holding the link; and the invention consists of a coupling-chain, which is pivoted to a longitudinally-adjustable slide-piece of the draw-bar, and operated from the side of the car by a lever mechanism connected to the main link of the coupling-chain, and of an adjusting mechanism by which the coupling-chain is drawn taut when placed in position on the draw-bar of the next car.

It also consists of a coupling-hook pivoted to the slide-piece of the draw-bar, said coupling-hook forming, with the coupling-chain of the next car, an auxiliary coupling for the cars.

In the accompanying drawings, Figures 1 and 2 represent a vertical longitudinal section and a plan of my improved car-coupling, showing the coupling raised and in the act of being coupled. Fig. 2^a is a detail of the draw-bar and auxiliary coupling-hook. Figs. 3 and 4 are a vertical longitudinal section and a plan, showing the cars coupled and the coupling-chain drawn taut; and Fig. 4^a is a vertical transverse section, on a larger scale, of the main link of the coupling-chain.

Similar letters of reference indicate corresponding parts.

C C in the drawings represent the draw-bars, which are applied in any approved manner to the bottom frame of the cars. The draw-bars C C are provided with hook-shaped ends, and provided at their lower part, back of the hooks, with slots that serve to guide a slide-piece, b. The slide-piece b serves also as a screw-nut for a spindle, c, that is supported in bearings of the draw-bar and extended back of a shoulder, q, of the same, it being provided immediately back of the shoulder with a collar, r, by which the spindle bears against

the shoulder q, so that it can resist the strain exerted upon it in longitudinal direction. The spindle c is provided at its rear end with a worm-wheel, d, with which gears a worm, f, that is splined to a transverse crank-shaft, e, 55 which extends across the bottom frame of the car, and is guided in slotted side straps, e', as shown in Fig. 3. The crank-shaft e is turned by cranks g at its ends in one or the opposite direction. It is rigidly connected at its center with the draw-bar C by a central barrel-shaped bearing, s, so that it is compelled to follow the motions of the draw-bar C. By turning the crank-shaft e in one or the opposite direction, the slide-piece b can be adjusted 60 forward or backward. To the slide-piece b is pivoted the U-shaped link B of the coupling-chain, which consists, besides the link B, of a short intermediate link, a, and a longer main link, A. To the pivot of the slide-piece b is 65 further applied a coupling-hook, D, which is engaged by side lugs of the link B, so that the latter takes the hook D along when it is lifted, as shown in Fig. 2^a, while otherwise the hook D is free to move in upward direction, as shown 70 by the relative positions of link B and hook D in Figs. 1 and 3.

The main link A is provided at one side with a guide-rod, n, of square cross-section, which is rigidly attached to fixed lugs n' at one 80 side of the link A. A connecting-piece, m, having a heel, m', is guided by a square opening on the fixed guide-rod n of the main link A, and firmly attached by a screw-nut, h², as shown in Fig. 4^a, to the outer end of a jointed 85 lever, h h', the arm h of which is rigidly attached to a laterally-sliding and axially-turning rod, i, that turns in bearings k k at the end of the bottom frame of the car. The ends of the transverse rod i are bent at right angles, so as to form handles i', by which the guide-rod i can be pushed sidewise and turned in its bearings k k, as required. The lever h' is pivoted to the lever-arm h at o in such a manner that the lever h' can only be turned in 90 upward direction, but not in downward direction, as a stop-shoulder of the lever-arm h prevents its motion in downward direction. As soon as the lever-arm h is lifted by the rod i, the lever h' forms a straight rod therewith, as 100

shown in Fig. 1, while when the lever-arm *h* is lowered with the rod *i* the outer lever, *h'*, turns on the pivot *o* and assumes an angular position to the arm *h*, as shown in Fig. 2. By 5 the connecting-piece *m* and its heel *m'*, the coupling-chain is raised or lowered with the levers *h h'*, as the heel *m'* "takes" below one side of the main link *A*, as shown clearly in Fig. 4, and also moved laterally in connection with 10 the laterally-shifting motion of the rod *i*.

My improved coupling is operated as follows: The brakeman takes hold of the handle *i'* of the rod *i*, moves the same laterally toward him, and turns the same simultaneously in upward direction, so that it moves through an angle of somewhat more than ninety degrees. By means of the jointed lever *h h'*, the connecting-piece *m m'* moves along the guide-rod *n* of the main link *A* to the fore end of said rod, 15 and lifts the coupling-chain from its lower pendent position (shown in dotted lines in Fig. 1) into the raised position shown in Figs. 1 and 2. The rod *i* is now pushed laterally away from the brakeman until the lever-arm *h* is 20 stopped by the central bearing, *k*. The handle *i'* is now dropped, whereby the main link *A* is placed over the hook-shaped end of the draw-bar *C* of the next adjoining car. The cars are thus connected sufficiently, so that they 25 can be readily made up in trains. When the train is made up, the coupling-chain of each coupling is pulled taut by the brakeman, who turns the crank *g*, so that by the motion of the shaft *e*, worm *f*, worm-wheel *d*, and screw-spindle *c* the slide-piece is moved backward, and 30 thereby the coupling-chain *B a A* is stretched taut, as shown in Fig. 3. The auxiliary coupling of the cars is then accomplished by placing the coupling-chain of the next adjoining 35 car over the coupling-hook *D* of the first car, for which purpose the coupling-chain is lifted by the lever *h h'* and rod *i* high enough that the main link *A* is intermediately between the link *B* and the coupling-hook *D*. The handle 40 *i'* is then dropped, so that the main link *A* drops over the hook *D*. In this manner the cars are doubly coupled for the regular running of the trains, the main connection being made by the tautly-stretched coupling-chain of 45 one car, and the auxiliary connection by the coupling-chain of the next car and the coupling-hook of the first car. To uncouple the cars, the same operations are accomplished in reverse order.

50 My coupling has the advantage that it can be coupled quickly and conveniently from

either side of the car without danger to life and limb; that it can be coupled with the common draw-head and coupling-pin heretofore in use, and that it can be coupled with cars of different height and having buffers of varying lengths. It also enables the coupling of cars when they have approached very closely to each other, as the coupling-chain can be drawn taut, so as to produce, notwithstanding the short distance 65 between the buffers, the reliable coupling of the cars.

Having thus described my invention, I claim as new and desire to secure by Letters Patent—

1. The combination of a slotted draw-bar, 70 having a hook-shaped end, a coupling-chain composed of several links, the rear link being pivoted to a slide-piece of the draw-bar, means connected to the slide-piece for adjusting the same in forward or backward direction on the 75 draw-bar, and a lever mechanism connected to the outermost link, whereby the coupling-chain is raised or lowered and shifted laterally, substantially as and for the purpose set forth.

2. The combination of a slotted draw-bar, *C*, 80 having a hook-shaped end, slide-piece *b*, coupling-chain *B a A*, pivoted by link *B* to the slide-piece *b*, screw-spindle *c*, turning on bearings of the draw-bar, a worm-wheel, *d*, transverse 85 crank-shaft *e*, guided in slotted side straps, *e'*, and having a central worm, *f*, and cranks *g* at the ends, substantially as set forth.

3. The combination of a slotted draw-bar, *C*, 90 having a hook-shaped end, and slide-piece *b*, a coupling-chain, *B a A*, pivoted to the slide-piece *b*, pivoted levers *h h'*, having connecting-piece *m m'* at the outer end, the latter being guided along the rod *n* of the main link *A*, and a laterally-sliding and auxiliary turning rod, 95 *i*, having handles *i'*, substantially as set forth.

4. The combination of a slotted draw-bar having a fork-shaped end, a coupling-chain pivoted to the slide-piece of the draw-bar, a coupling-hook, also pivoted to the slide-piece, 100 means to adjust the coupling-chain and coupling-hook forward or backward, and means whereby the same are raised or lowered for coupling or uncoupling, substantially as described.

In testimony whereof I have signed my name to this specification in the presence of two subscribing witnesses.

PETER MADSEN.
